[57] CLAIM

The ornamental design for an electric griddle or similar article, as shown and described.

DESCRIPTION

FIG. 1 is a top rear perspective view of an electric griddle or similar article showing our new design;

FIG. 2 is a top plan view thereof on an enlarged scale;

FIG. 3 is a front elevational view thereof on the same scale;

FIG. 4 is a bottom plan view thereof on the same scale;

FIG. 5 is a rear elevational view thereof on the same scale;

FIG. 6 is a right side elevational view of FIG. 2, the left side elevational view being a mirror image thereof; and FIG. 7 is a fragmentary, sectional view, as taken along line 7—7 of FIG. 5 in the direction of the arrows, so as to show details of means mounting and spacing a handle on one side of said electric griddle, means mounting and spacing the handles on opposite sides of said electric griddle being alike.

The handles on opposite sides of said electric griddle are like units of a handle shown and described in an application of Steven R. Groner for design patent entitled handle for a cooking or heating utensil, as filed simultaneously herewith, and as assigned commonly herewith.
